UNITED STATES PATENT OFFICE.

FRANK W. MERRICK, OF BOSTON, MASSACHUSETTS.

PRESSER-FOOT-LIFTING MECHANISM FOR SEWING-MACHINES.

SPECIFICATION forming part of Letters Patent No. 629,108, dated July 18, 1899.

Application filed March 16, 1896. Serial No. 583,476. (No model.)

To all whom it may concern:

Be it known that I, FRANK W. MERRICK, a citizen of the United States, residing at Boston, in the county of Suffolk and State of Massachusetts, have invented certain new and useful Improvements in Presser-Foot-Lifting Mechanism for Sewing-Machines, of which the following is a specification, reference being had therein to the accompanying drawings.

My invention has for its object to provide a presser-foot-lifting mechanism for sewing-machines which shall operate automatically to raise the presser-foot.

My present invention is an improvement on that shown and described in my Patent No. 582,792, granted May 18, 1897.

The construction and operation of a device embodying my invention is fully set forth in the following description, and the novel features thereof are pointed out and clearly defined in the claims at the end of this specification.

In the accompanying drawings, to which particular reference is hereinafter made, Figure 1 is a view in elevation representing the head of a sewing-machine with my invention applied thereto. Fig. 2 is an end view of the parts shown in Fig. 1 from the right of the latter figure. Figs. 3 and 4 are views showing the clamping devices in detail. Figs. 5, 6, and 7 are perspective views of the movable sleeve or bearing for the presser-bar, the clamping-block, and the threaded collar or nut, respectively.

At 1 is represented the head of a sewing-machine; at 2, the awl-bar; at 3, the awl carried by the said awl-bar; at 4, the presser-foot, and at 5 the presser-bar. The machine is provided, preferably, with the usual lever operated by the foot for lifting the presser-foot and presser-bar when desired, and also with the usual hand-operated lever, by which the operator is enabled to raise the presser-foot by hand when desired. These parts I have not deemed it necessary to show, as they may be of any usual or preferred construction. In like manner the awl-bar is operated in any well-known or suitable manner.

At 9 is a sleeve which surrounds the upper end of the presser-bar 5, the said sleeve being fitted to a bearing provided therefor in

the upper part of the head 1 and being free to slide up and down in such bearing. The upper extremity of the presser-bar extends above the upper end of the said sleeve and is borne upon by the free end of a leaf-spring 10, which latter is secured to the arm of the machine, as will be clear from Fig. 1. The said spring 10 acts to hold the presser-foot 4 normally pressed upon the upper surface of the work. A second leaf-spring 11 is secured by means of a screw 12 or equivalent device to the under side of the spring 10. The free end of the said spring 11 bears upon the upper end of the sleeve 9 and tends to force the sleeve downwardly into its lowest position. The pressure exerted by said spring upon the sleeve is adjusted by means of screw 111, applied to spring 10. The upper end of the sleeve 9 is screw-threaded and has applied thereto the adjusting-nut 13, above which is the lock-nut 14. A washer 15, preferably of sound-deadening material, is placed upon the said upper end of the sleeve 9 below the adjusting-nut 13, the said washer lying upon the top of the head 1. By means of the adjusting-nut 13 the vertical position of the sleeve 9 may be varied, as will be obvious. In practice, however, it is not usually necessary to effect a change in the vertical position of the said sleeve 9 by means of the said adjusting-nut 13. The sleeve 9 is formed as shown, Figs. 3 and 5, it being provided with an offset portion 16, which serves to connect the upper portion of the sleeve 9 with the small lower portion 17. Between the portions 17 and 9 and opposite the offset portion 16 the sleeve is cut away, and there is a vertical slot 171 in the offset portion, as will be clear from Fig. 5. In the opening thus formed by cutting away the sleeve I place a clamping-block 18, which has a vertical cylindrical hole 181 therethrough, in which is fitted a nut or collar 19, said nut or collar being interiorly screw-threaded to correspond with the screw-threads on the presser-bar or on that portion of said bar with which the nut or collar 19 co-operates. The said screw-threads have a quick turn, and the nut or collar 19 is free to revolve in the vertical hole or bearing therefor which is formed in the block 18. If the sleeve 9 be held rigidly while the collar and block are free, the presser-bar may

be caused to move vertically with reference to said sleeve, the collar 19 rotating around the bar as the latter is moved. If, now, the collar 19 be firmly clamped and prevented from rotating on the bar, the sleeve and bar will be locked together and cannot be moved independently.

For the purpose of preventing the sleeve 9 and the clamping-block 18 from rotating on the presser-bar the clamping-block 18 is formed with a vertical groove 201, corresponding in position with the vertical slot 171 in the said offset portion 16 of the sleeve 9. The slot in the said offset portion and the groove 15 in the said block receive the awl-bar 2, as will be clear from Figs. 3 and 4, and the said awl-bar serves as a guide for the sleeve 9 and clamping-block 18 in their vertical movement to prevent their rotating relatively to the said presser-bar. For the purpose of clamping the collar 19 rigidly onto the presser-bar I form the clamping-block 18 slightly beveling on its upper surface, as shown at 21, Fig. 3, so that said clamping-block may be tilted 20 slightly relatively to the sleeve 9. A very slight tilting of the clamping-block 18 serves to clamp the threaded collar 19 and prevent the collar from rotating. If, now, the clamping-block be lifted, the presser-bar, collar, 25 and sleeve will move upwardly with it. For the purpose of tilting the clamping-block, as also of lifting it vertically, the said block is provided with a projection or tailpiece 22, with which the free end of the bent arm 23 30 engages.

For the purpose of operating the lifting-arm 23 I secure it rigidly to a rock-shaft 25, which is journaled in the frame of the machine, as shown, and which is rocked by means of an 40 eccentric 26 on the main shaft 27. The strap 28 of the eccentric is pivoted to an arm 29, which is secured to the rock-shaft 25 at the opposite end of the said rock-shaft from that at which the lifting-arm 23 is secured. (See 45 Fig. 1.) These parts are of well-known construction and do not require a detailed description. As is well known, they may be adjusted to vary the throw of the arm 23 or the time of its movement.

50 As grooving attachments and similar devices are frequently employed in machines to which my invention is applicable and are arranged to work slightly above the surface of the work-support or work-plate, provision 55 should be made for preventing the presser-foot from being forced downwardly onto these devices or onto the work-plate when there is no work in the machine. To provide for limiting the descent of the presser-foot, I employ 60 a block 30, which is provided with a hole, through which the presser-bar passes and which is split at one side and provided with laterally-extending lugs 31 32, through which the threaded end of a bolt 33 is screwed. The 65 shank of the bolt 33 projects through a block 50, set to slide in a vertical slot 34 in the front of the head of the machine. The split block

30 and its clamping-bolt 33 are so set on the presser-bar that at the lowest position of the presser-bar and presser-foot the block 50 will 70 bottom in the slot 34, and it will be clear that in this way the lowest point to which the presser-foot may descend may be governed. To prevent noise, the bottom of the slot 34, with which the block 50 engages, may be provided with a layer or piece 501 of sound-deadening material, as leather or the like. 75

The operation of the device is as follows: When work is placed in the machine, the presser-foot may be raised either by means 80 of the usual foot-operated lifting mechanism or by hand-operated lifting mechanism. The work being in place, the presser-foot is released and by means of the spring 10 is forced downwardly onto the upper surface of the 85 work and bears thereon, holding the work firmly until in the movement of the machine the work is to be fed forward. Just before the work is fed forward the lifting-arm 23 is operated by means of the rock-shaft 25 and 90 its operating mechanism, and when it engages the tailpiece 22 the threaded collar is gripped and prevented from rotating. This locks the sleeve 9 and presser-bar 5 together. The further lifting movement of the arm 23 95 raises the sleeve and bar together and lifts the presser-foot from the work, so that it is free to be fed forward. At the end of the feed movement the lifting-arm 23 moves downwardly, freeing the clamping device and 100 allowing the spring 10 to force the presser-bar and presser-foot downwardly onto the work. At the same time the spring 11 acts to force the sleeve 9 downwardly, returning 105 said sleeve to its lowest position. If the presser-foot upon its descent meets a thicker portion of the work, the descent of the presser-bar will be less, but the descent of the sleeve 9 will be the same, regardless of the thickness 110 of the work, so that the action of the sleeve 115 is the same under all conditions of stock. Since the bar is locked to the sleeve before the latter is lifted, the upward movement or lift of the bar and sleeve must be equal at all times. The sleeve 9, as will be obvious, 120 may be shortened somewhat without departing from the spirit of the invention, forming what might more properly be designated as a "collar," or it may be made in the form of two collars separated from each other and 125 rigidly connected. It is to be noted likewise that the function of the sleeve 9 as a bearing is not essential to the operation of my device, although, as previously described, it is important in distributing the lateral strain 130 which occurs during the lifting operation and in relieving the presser-bar from that lateral strain. The function of the sleeve or collar 9 as an adjustable connection intermediate the adjusting-nut 13 and the lifting-arm 1 135 consider of greater importance than its function as a bearing.

It will be noted that by the employment of my invention the presser-bar and presser-

foot are lifted upwardly a predetermined distance which is uniform whether the work be thick or thin. It will also be noted that the clamping and lifting of the presser-bar is effected smoothly without jar or shock and that all lateral strain and consequent friction is removed from the presser-bar in the operation of clamping and lifting it and is borne by the vertically-movable bearing or sleeve 5 9, which on account of its large bearing-surface reduces the effect of the lateral pressure to a minimum.

What I claim is—

1. The combination with the presser-foot 15 and the presser-bar of a sewing-machine, the said presser-bar being threaded throughout a portion of its length, of a threaded collar revolvable on said bar, a clamping and lifting lever engaging said collar and means to actuate 20 said lever to turn it against said collar so as to clamp the latter and raise it and the presser-bar by part of the movement which is communicated to the lever, substantially as described.

2. The combination with the presser-foot 25 and the presser-bar of a sewing-machine, the said bar being threaded throughout a portion of its length, of a movable bearing for the said presser-bar, a threaded collar on said bar, 30 a clamping and lifting lever engaging said collar and said bearing, and means to actuate said lever to clamp the collar and raise the bearing and presser-bar in unison through part of the movement which is communicated 35 to the lever, substantially as described.

3. The combination with the presser-foot 40 and presser-bar of a sewing-machine, the said presser-bar being threaded throughout a portion of its length, of a movable bearing for the said presser-bar, means to adjust the po-

sition of said movable bearing vertically, a threaded collar on said bar, a clamping-lever engaging said collar and said bearing and means to actuate said lever to clamp the collar and raise the bearing and presser-bar in unison through part of the movement which is communicated to the lever, substantially as described. 45

4. The combination with the presser-foot 50 and presser-bar of a sewing-machine, the said presser-bar being threaded throughout a portion of its length, of a movable bearing for the said presser-bar, a leaf-spring engaging the presser-bar to press it downwardly toward the work, a leaf-spring engaging the said movable bearing to press it downwardly to its lowest position, a threaded collar on said presser-bar, a clamping-lever engaging the said collar and said bearing and means to actuate 55 said lever to clamp the collar and raise the bearing and presser-bar in unison through part of the movement which is communicated to the lever, substantially as described.

5. The combination with the presser-foot 60 and presser-bar of a sewing-machine, said bar being threaded throughout a portion of its length, of a nut, a threaded collar on said bar, a clamping-lever engaging said collar and actuating means for said lever, and an adjustable connection intermediate the nut and said 65 clamping-lever whereby to vary the position of the latter vertically, substantially as described.

In testimony whereof I affix my signature in presence of two witnesses.

FRANK W. MERRICK.
